DESIGN FOR A FOLDING DISPENSING PACKAGE OR SIMILAR ARTICLE

Leroy L. Salfisberg, South Orange, N. J., assignor to Ivers-Lee Company, Newark, N. J., a corporation of Delaware

Application May 27, 1942, Serial No. 107,018

Term of patent 14 years

To all whom it may concern:

Be it known that I, Leroy L. Salfisberg, a citizen of the United States and a resident of South Orange, in the county of Essex and State of New Jersey, have invented a new, original, and ornamental Design for a Folding Dispensing Package or Similar Article, of which the following is a specification, reference being had to the accompanying drawing, forming part thereof.

Figure 1 is a perspective view of a folding dispensing package showing my new design, with the package unfolded for opening.

The characteristic features of my design reside in the portions shown in full lines.

I claim:

The ornamental design for a folding dispensing package or similar article, as shown and described.

LEROY L. SALFISBERG.
